W. STEVENSON,
FUEL FEEDING MEANS FOR INTERNAL COMBUSTION ENGINES,
APPLICATION FILED SEPT. 15, 1916.

1,235,254.

Patented July 31, 1917.

WITNESS:

Wm. D. Bell.

William Stevenson

BY
John Seward,
ATTORNEY

UNITED STATES PATENT OFFICE.

WILLIAM STEVENSON, OF MORRISTOWN, NEW JERSEY.

FUEL-FEEDING MEANS FOR INTERNAL-COMBUSTION ENGINES.

1,235,254.

Specification of Letters Patent. Patented July 31, 1917.

Application filed September 15, 1916. Serial No. 120,281.

To all whom it may concern:

Be it known that I, WILLIAM STEVENSON, a citizen of the United States, residing at Morristown, in the county of Morris and 5 State of New Jersey, have invented certain new and useful Improvements in Fuel-Feeding Means for Internal-Combustion Engines, of which the following is a specification.

This invention relates to internal combustion engines of the class which depend upon gasolene or a similar volatile combustible liquid as the fuel, and it contemplates utilizing, to form the combustible, the vapor given off by such a liquid concurrently with the 15 use in the regular way of the liquid itself in the form of a spray, whereby to obtain an economy of fuel, an increase of power, and greater facility of starting the motor. My invention consists in the combination, 20 with the manifold or like intake element of an internal combustion engine of the class indicated, and a carbureter including a spraying device for the intake element and a float-chamber or other liquid fuel reserve 25 chamber, of a tubular connection extending from said chamber above the normal liquid level therein to the intake. By taking the vapor direct from the float-chamber or equivalent to the intake I make it possible 30 to employ a very simple form of connection and at the same time take advantage of a source that is copious in vapor on account of the excitation of the liquid fuel incident to its ingress to and egress from said chamber.

My invention further consists in forming the inlet end of said connection in a manner to prevent the fuel in liquid form from being drawn thereinto at certain times, as when 40 the carbureter is flooded.

My invention further consists in forming the delivery end of said connection in a manner to insure against back-firing from the engine reaching the float-chamber, and 45 so as to obtain certain other practical results, as simplicity of construction and facility of attaching the connection to the intake.

In the accompanying drawing,

50 Figure 1 is a view showing an intake manifold and carbureter of a conventional type, and my appliance associated therewith, the said parts appearing partly in side elevation and partly in section;

55 Fig. 2 is a sectional view of the intake end of said appliance, the plane of the section

being substantially coincident with the axis of said end;

Fig. 3 is a sectional view on the line 3—3 of Fig. 2;

Fig. 4 is a plan of the elbow shown in Fig. 3; and,

Fig. 5 is a side elevation, partly in section, of the nipple at the intake end of the appliance.

The intake *a* for the engine *b* shown by broken lines includes the branched portion *c*, or manifold proper, connected to the engine and the air passage *d*, having a throttle valve *e*, of a carbureter indicated generally by the reference character *f*; in the air passage *d* is a Venturi tube *g* into which discharges upwardly the spray nozzle *h* which is supplied with liquid fuel through the port *i* from the float-chamber *j*, the float or equivalent level-controlling means *k* of which maintains the level of the liquid fuel in said float chamber at, or at least not higher than, the outlet end of the spray nozzle *h*. *l* is the usual air inlet opening in the top of the float-chamber, serving to admit the atmospheric pressure necessary to cause delivery of liquid fuel at the spray nozzle on reduction of pressure in the intake *a* due to the aspiration of the engine. The parts so far described are elements common to any internal combustion engine employing a carbureter.

Above the normal liquid level in the float-chamber *j* I connect thereto a tubular conductor *m* which leads to and is connected with the unbranched portion or stem of the manifold proper. The communication afforded between the float chamber and the intake *a* by such conductor is restricted so that the volume of fluid capable of passing therethrough is less than that capable of entering the air inlet *l* of the float-chamber. In consequence of this construction, while atmospheric pressure remains available to maintain delivery of the liquid fuel at the spray nozzle *h*, so that the engine is fed with a mixture of air (passing through the venturi *g*) and the atomized liquid fuel in the usual way, the vapor given off by the liquid fuel in the float-chamber, and constantly replenished on account of the excitation incident to the ingress to and egress from said chamber of the liquid fuel, together with some of the air admitted at the inlet *l*, is drawn as a mixture with said air directly into the intake *a* and so into the en-

gine. Since the fuel as thus fed through the connection *m* to the engine is a most highly divided form thereof (vapor), the operation of the engine is of course very considerably stimulated, in consequence of which I am able to obtain not only a large saving of fuel but a very appreciable increase of power, and besides greatly facilitate the starting of the engine.

10 As preferably employed, the conductor *m* is constructed as follows:

It includes the pipe or conductor proper *n* formed of flexible metallic tubing so that it may by bending be adapted to the structural conditions of any engine to which the appliance may be fitted. Each end thereof is preferably expanded, as indicated at *n'* and *n''* in Figs. 1 and 2, respectively.

15 The tapered upper end *o'* of a nipple *o* (Fig. 5) formed midway its length as a nut *o''*, forms a sealed joint with the flared end *n'* of the pipe *n*, which joint is maintained by the union *p* (Fig. 1) swiveled on said flared end and screwed onto the upper end of the 20 nipple. Said nipple is threaded at its lower end as shown in Fig. 5 and is screwed into a suitable hole tapped into the top wall of the float-chamber. Said nipple is bored to form a relatively large chamber *o³* extending 25 well up into the same, the outlet from which is an orifice *o⁴* that is restricted to a diameter less than that of the air inlet *l* of the float-chamber, so that the volume of fluid capable of passing therethrough is less than 30 that of said air inlet, as already explained. Air from the inlet *l* flows direct, without downward deflection, to the mouth of the conductor, so that in case of flooding only 35 gaseous fluid, and not raw or liquid gasoline, will be drawn into the conductor, even the 40 tendency of capillary attraction to conduce to the sucking up of the liquid gasoline into the conductor being prevented by enlarging the intake end thereof, as at *o³*.

45 At the other end of the pipe *n* is a fitting including a nipple, a union for connecting the nipple to said end of the pipe, an elbow, a valve-chamber connected with said nipple by the elbow and containing a valve, 50 and another nipple connecting the valve-chamber with the manifold proper of the intake *a*. The first nipple *q* has one end tapered and forming a sealed joint with the flared end *n²* of the pipe *n* and is externally 55 threaded at both ends and includes an intermediate nut *q'*. The joint between the nipple and said end of the pipe is maintained by the union *r*, which is screwed onto one end of the nipple and swiveled on said end of the 60 pipe. The elbow *s* has the other end of the nipple screwed into the same at one end and into the other end of the elbow is screwed

the closed end of the cup-shaped valve-chamber *t*. Into the open end of said valve-chamber is screwed one end of the nipple *u*, 65 the other end of which is screwed into the manifold proper of the intake *a*, said nipple having an enlarged intermediate nut *u'* formed thereon. One or more orifices *t'* are formed in the bottom of the valve-chamber *t*, these being adapted to be closed by a valve *v* which is held against the inner or engine side of the bottom wall of the valve-chamber by a spring *w* coiled about a screw *x* and interposed between the head *x'* thereof and the valve, said screw penetrating the bottom of the valve-chamber and having an adjusting nut *x²* screwed on its free end. 70

75 The spring *w*, by adjusting the nut *x²* on the screw *x*, is set so that it will yield to the pressure developed in pipe *n* when the engine is running. Following each suction of the engine it seats, in consequence of which, should the pressure at the engine side of the valve preponderate over that at the opposite 80 side thereof, as in the case of a back-fire, it seals off the communication through the conductor *m*, preventing the fire from reaching the float-chamber.

Having thus fully described my invention, 90 what I claim as new and desire to secure by Letters Patent is:—

1. In combination, with the intake of an internal combustion engine and a carbureter including a liquid-delivery device for the intake and a covered constant-level volatile liquid reserve chamber delivering to said device and having above the normal liquid level therein an air-inlet, a tubular conductor connecting said chamber above said level 95 with the intake and having a relatively enlarged mouth at the chamber end thereof, the top of said chamber permitting fluid flow, without downward deflection, from the air-inlet to said enlarged mouth of the conductor. 100

2. A vapor feeding conductor for connecting the constant level liquid fuel reserve chamber of a carbureter with the intake of an internal combustion engine including a pipe adapted to be attached at one end to said chamber, a valve chamber, a nipple screwed into the intake and having a screw-thread connection with the valve-chamber, an elbow having screw-thread connection with the valve-chamber, and having said pipe operatively connected at one end therewith and a check-valve housed in the valve chamber and normally spring held toward said fuel reserve chamber to close the 110 passage through said conductor. 115

In testimony whereof I affix my signature.

WILLIAM STEVENSON.
